Willy H. Wong(57) **CLAIM**

The design for a grill, as shown and described.

DESCRIPTION

FIG. 1 is a front view of a grill showing our new design;

FIG. 2 is a back view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines show portions of the grill for illustrative purposes only and form no part of the claimed design.
